UNITED STATES PATENT OFFICE.

ROBERT J. MULVEY, OF CHICAGO, ILLINOIS.

GARMENT FASTENER.

1,411,060.

Specification of Letters Patent. Patented Mar. 28, 1922.

Application filed March 21, 1921. Serial No. 453,970.

To all whom it may concern:

Be it known that I, ROBERT J. MULVEY, a citizen of the United States, and a resident of the city of Chicago, county of Cook, and State of Illinois, have invented certain new and useful Improvements in Garment Fasteners, of which the following is a specification.

My invention relates to improvements in garment fasteners, more particularly to the usual snap fasteners, and has for its object the provision of a metal guard for protecting the point of the fastening wire.

Other objects will appear hereinafter.

The invention consists in the combinations and arrangements of parts hereinafter described and claimed.

The invention will be best understood by reference to the accompanying drawings forming a part of this specification, and in which,

Fig. 1 is a bottom plan view of the fastener;

Fig. 2, a fragmentary side view thereof, with a part broken away;

Fig. 3, an enlarged fragmentary detail, showing the wire loop upon which the guard plate is mounted;

Fig. 4, an enlarged detail of the guard plate;

Fig. 5, a bottom plan view of a fastener provided with a modified form of guard plate;

Fig. 6, a fragmentary side view thereof, with a part broken away;

Fig. 7, an enlarged detail side view of a modified form of guard plate; and

Fig. 8 a plan view thereof.

The form of construction illustrated in Figs. 1 to 4 inclusive, comprises a metal disk 10 having a knob 11 extending from the center of its upper face and an outer flange 12 curved toward the lower face. A securing wire 13 of spring steel is fastened under said curved flange, substantially entirely around said disk and is provided with a loop portion 14 extending inwardly from said flange, and then continues in the form of a curved or S-shaped portion 15 seated on the lower face of said disk. The free end of said S-shaped portion is provided with a hook 16 adapted to engage within the loop 14. Inward of this hook 16 a wire is provided with an elbow 17 to allow the hook to

be readily depressed for removal from said loop.

This hook was formerly left unprotected and, therefore, enabled to engage and injure cloth or garments with which it came in contact. It is the main object of this invention to protect or cover this hook end, and this I do by providing a metal guard plate 18 having forwardly extending flanges 19 and a rear flange 20. This plate is mounted on the loop 14 by bending the forward flanges 19 over the loop and catching the rear flange 20 under the flange 12 of the disk, so that it engages back of the wire 13, as shown in the drawings.

In the form of construction illustrated in Figs. 5 to 8 inclusive, the fastening means is constructed substantially the same as the form already described, except that the loop is substantially diminished, and a slight curve 22 is provided in the wire upon which the modified guard plate 23 is mounted, its hook end 24 engaging over said curve and bearing under the flange 12. The free end of this guard plate is provided with a curved or dished portion 25, to receive and protect the hook end 16 of the wire.

In fastening this device to the garment, in either of the two forms, the hook end of the wire attached to one end of the S-shaped curve is passed through the garment and the member turned until the garment has passed to the other end of the S-shaped curve. The hook is then re-passed through the garment and fastened beneath the protecting plate. The plate thus protects the point from marring or injuring a garment, and is also effective in retaining the hook in position.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent, is:

1. A device of the class described comprising a metal disk having an outer curved

flange; a securing wire fastened under said flange and having a loop and a hook end engaging within said loop; and a guard member mounted on said device, adapted to receive and protect said hook end.

2. A device of the class described comprising a metal disk having an outer curved flange; a securing wire fastened under said flange and having a loop and a hook end; and a guard member fastened to said flange, and loop adapted to receive and protect the hook end of said wire.

3. A device of the class described comprising a metal disk having an outer curved flange; a securing wire having a portion fastened under said flange and having an elbow and a hook at its end; and a guard member having a bent end fastened under said flange and its free end adapted to receive and protect the hook end of the wire.

4. A device of the class described comprising a metal disk having an outer curved

flange; a securing wire having a portion fastened under said flange and being provided with a loop and a hook end; and a guard plate having a bent end fastened under said flange and a free end fastened over said loop, said plate engaging and protecting said hook end.

5. A device of the class described comprising a metal disk having an outer curved flange; a securing wire fastened under said flange and having a hook end; and a guard member having a curved end fastened over said wire and under said flange and being provided with a curved free end to retain and protect said hook end.

In testimony whereof I have signed my name to this specification in the presence of two subscribing witnesses.

ROBERT J. MULVEY.
